UNITED STATES PATENT OFFICE.

CHARLES S. HARDY, OF SAN DIEGO, CALIFORNIA.

SHEET-METAL CAN.

1,160,074.

Specification of Letters Patent.

Patented Nov. 9, 1915.

Application filed August 7, 1914. Serial No. 855,618.

To all whom it may concern:

Be it known that I, CHARLES S. HARDY, a citizen of the United States, and a resident of San Diego, in the county of San Diego and State of California, have invented an Improvement in Sheet-Metal Cans, of which the following is a specification.

My present invention relates generally to sheet metal cans, and more particularly to a sheet metal can or pail, the body of which is provided with a rolled finished upper edge for the reception of the usual slip cover in order that the can or pail may be used continuously and for various purposes after its original contents have been removed, my object being to provide an extension top for the can body of such a nature that the original contents of the can may be hermetically sealed, said extension top being adapted to receive the ordinary slip cover and being separable from the can body in such a manner as to leave the finished rolled upper edge of the body free and unbroken for the reception of the cover in its after use. I preferably accomplish these objects by means of an extension top applicable to a can body having a finished rolled upper edge and having a rim portion scored circumferentially to form a rip strip which is in the first instance soldered to the said finished rolled edge of the can body, the said extension top being adapted to telescopingly receive the usual slip cover which, upon removal of the supplemental top by means of the rip strip, may be thereafter readily associated with the finished rolled edge of the can body in the usual manner.

In the accompanying drawing, which illustrates my invention, Figure 1 is an elevation of a can or pail constructed in accordance with my invention, with the supplemental top in position to hermetically seal the can body and with the usual slip cover shown in dotted lines. Fig. 2 is a similar view of the upper portion of the can illustrating the supplemental top partially removed. Fig. 3 is a vertical section through the upper portion of the hermetically sealed can as shown in Fig. 1. Fig. 4 is a similar view with the slip cover disposed thereon and as the can or pail is sold with its original contents, and Fig. 5 is another similar view showing the cover associated with the upper finished edge of the can body in use after the supplemental top has been removed and the original contents of the

can or pail exhausted and constituting a slight modification as regards Fig. 3.

Referring now to these figures I have shown at A a can body or pail, for instance for the transportation and sale of lard and commodities of this nature and which is provided with a finished rolled upper edge A' as clearly seen in Figs. 3 to 5 inclusive, and a circumferential bead A² below this edge, adapting the can or pail body A to use in accordance with my invention. With such a can body or pail as just described I preferably utilize a supplemental top B which, as best shown in Figs. 3 and 4 includes a top plate B', the circumferential edge of which is hermetically sealed by means of a rolled or soldered joint B² to the depending rim B³, the lower free edge of which telescopes upon the rolled finished edge A' of the body A and is secured thereto in air-tight relation by solder. This rim B³ of the supplemental top is intermediately and annularly scored at B⁴ whereby its lower edge which is secured to the can body in the manner just described constitutes a rip strip B⁵, said rip strip having an extension B⁶ at one end for engagement by the usual rip strip key C as seen in Figs. 1, 2 and 3. In this connection it will be noted particularly from Fig. 4 that the rim B³ of the supplemental top tapers inwardly and upwardly and that the outer edge of the rolled joint B² between its plate B' and the rim B³ is preferably in substantially the same vertical plane with the outer peripheral face of the rolled body edge A', thus adapting the supplemental top B to receive the usual slip cover D in the manner best shown in Figs. 4 and 5 and which cover is adapted to be associated either with the finished rolled edge A' of the body A, as seen in Fig. 5, or with its bead A², the body edge A' being in both cases left unbroken upon the removal of the supplemental top B by ripping off the strip B⁵ in the usual manner, in order that the can or pail body with the slip cover D may be thereafter and following the removal of the original contents thereof, utilized for various purposes as may be desired. The same result may be accomplished in Fig. 3, where the slip cover will engage the circumferential bead A² when the supplemental top B is removed. Thus by the use of my invention, a soldered connection with the finished rolled edge of a can body is ripped to re-

move the supplemental sealing top of the can body, the rip strip itself constituting a part of such supplemental top and being formed by circumferentially scoring the latter, the said supplemental top itself consisting of a flanged rim and a top plate, the former of which is first soldered around the can body and the latter of which is then joined to the flange in such a manner as to

10 hermetically seal the can body.
It will be understood that where cover "B¹" is rolled on to extension "B³" that cover "B¹" will be provided with a suitable cement similar to that used in the ordinary
15 sanitary can, which together with the rolling of cover "B¹" makes a hermetically sealed joint.

I claim:

The combination of a can body having

a finished upper edge, a slip cover for the 20 can body adapted to be associated with the said finished edge thereof, and a supplemental top for hermetically sealing the body including a rim having a flanged upper edge and being intermediately and circumferentially 25 scored to form a rip strip along its lower edge, the said rip strip being telescopingly disposed upon and having a soldered connection with, the finished edge of the can body, and a top plate having a 30 rolled and soldered or cemented connection with the flanged upper edge of the rim and adapted to receive the slip cover in telescoping relation.

CHARLES S. HARDY.
